TYPEWRITING MACHINE

Chester W. Crumrine, Rochester, N. Y., assignor
to Electromatic Typewriters, Inc., Rochester,
N. Y., a corporation of New York

Application May 23, 1931, Serial No. 539,561

1 Claim. (Cl. 197—20)

This invention relates to improvements in type-writing machines, and particularly to power operated typewriting machines in which the operation of the printing instrumentalities is automatically controlled by means of a perforated master sheet.

The principal object of the invention is the provision of simple and inexpensive means for actuating the printing instrumentalities directly by the sheet controlled devices.

Another object of the invention is the provision of a power driven roller for actuating star wheels operatively connected with the printing instrumentalities, the engagement of said star wheels with said roller being selectively controlled by means of a perforated master sheet.

To these and other ends, the invention consists in the construction and arrangement of parts that will appear from the following description when read in conjunction with the accompanying drawing, the novel features being pointed out in the claim at the end of the specification.

The drawing represents a vertical transverse section of so much of a typewriting machine as is necessary to illustrate one possible embodiment of the invention.

This machine comprises a platen 1 with which a pivoted type bar 2 is adapted to cooperate to print on a work sheet arranged thereon. Although only one type bar and actuating means associated therewith is illustrated herein for the sake of clearness, it will be understood that the usual number of type bars may be employed. Power operated means comprising a power driven roller 3 are provided for actuating the type bars into engagement with the platen.

The power driven roller 3 has its surface provided with alternate depressions and projections for engagement with the arms 4 of a star wheel 5 revolvably mounted on one arm of a bell crank lever 6 pivoted on a fixed part and having its other arm operatively connected with one end of a toggle lever 7 by means of a link 8. The lever 7 is pivotally connected with the type bar at 9, and at its other end is pivoted to a toggle arm 10

pivoted on a fixed part. When the lever 6 is actuated, it swings the lever 7 to break the toggle and swing the type bar into engagement with the platen. A spring 11 connects the lever 6 with a fixed part and tends to swing the lever to resiliently press the star wheel into engagement with the power driven roller or a perforated master sheet 12 arranged thereon. Normally two arms of the star wheel engage the master sheet on which they ride idly until one of them meets a perforation in the sheet when it projects therethrough into engagement with one of the depressions in the roller, which turns the star wheel on its axis and cams it away from the power roller to swing the lever 6 and actuate the type bar to print.

Although only one embodiment of the invention is illustrated herein, it will be understood that this application is intended to cover such changes or modifications as come within the spirit of the invention or scope of the following claim.

I claim:

In an automatic typewriting machine having no keyboard, the combination with a platen, of a pivoted type bar movable into engagement therewith, a toggle lever pivotally connected to the type bar beneath the pivotal point of the type bar, said toggle lever having a downward extension, a bell crank lever including a pair of arms extending rearwardly from the pivotal point of the type bar, said bell crank lever at substantially right angles to each other, one of said arms extending laterally and the other upwardly, a link directly connecting the end of said upwardly extending arm of the bell crank with the downward extension of the toggle lever whereby rocking of the bell crank lever effects an endwise movement of said link, a star wheel mounted on the laterally extending arm of the bell crank lever, a type bar operating power driven roller having depressions cooperating with said star wheel, and a perforated master sheet on the roller controlling engagement of the star wheel with the type bar operating power driven roller.
